PACKAGE OF GOBLETS

Jean Fulchiron, Rive-de-Gier, France, assignor to Ver-series Hemain Freres, Rive-de-Gier, France, a societe
anonyme

Filed Mar. 4, 1965, Ser. No. 84,079

Term of patent 3½ years

(Cl. D58—2)

FIG. 1 is a perspective view of a package of goblets, showing my new design;

FIG. 2 is a front elevational view;

FIG. 3 is an end view;

FIG. 4 is a top plan view;

FIG. 5 is a bottom plan view on a reduced scale;

FIG. 6 is a fragmentary sectional view taken on line 6-6 of FIG. 3; and

FIG. 7 is a fragmentary sectional view taken on line 7-7 of FIG. 4.

I claim:

The ornamental design for a package of goblets, as shown.
